UNITED STATES PATENT OFFICE.

WILLIAM H. FULLINGTON, OF DAYTON, OHIO, ASSIGNOR TO THE AMERICAN PEG POOL TABLE COMPANY, OF COLUMBUS, OHIO.

DESIGN FOR A LEVER.

SPECIFICATION forming part of Design No. 30,444, dated March 28, 1899.

Application filed March 4, 1899. Serial No. 707,813. Term of patent 7 years.

To all whom it may concern:

Be it known that I, WILLIAM H. FULLINGTON, a citizen of the United States, residing at Dayton, in the county of Montgomery and State of Ohio, have invented and produced a new and original Design for a Lever, of which the following is a specification, reference being had to the accompanying drawings, forming part thereof, and in which like characters refer to correspondingly-formed parts.

My invention relates to a design for a lever for use more particularly in pleasure and amusement game-tables.

Figure 1 is a side elevational view of a lever embodying my new and useful design. Fig. 2 is a top plan view thereof. Fig. 3 is a bottom plan view thereof. Fig. 4 is a front end view thereof, and Fig. 5 is a rear end view thereof, these five views being deemed essential to fully illustrate my new and useful design.

The horizontal bar 10 is provided on its front end with a cylindrical portion 11, whose sides are at a right angle to the horizontal bar 10 and whose upper and lower surfaces 12 and 13, respectively, are parallel to said

bar 10, the top surface 12 of said projection 11 being some distance above the top surface of the bar 10. The front end of said bar 10 is circular to conform to the front wall of the portion 11. The rear end of the bar 10 is thicker than the front end thereof, said increased thickness being added to the lower edge of said bar 10, and on the rear end of said bar 10 is a bearing 14.

The essential feature of my design for a lever consists of a bar whose upper edge is straight, a cylindrical portion on one end of said bar and at right angles to the upper surface thereof, the opposite ends of said cylindrical portion being parallel with the upper surface of the bar, and a bearing in the opposite end of said bar.

What I claim is—

The design for a lever, as shown and described.

In witness whereof I have hereunto set my hand this 20th day of February, 1899.

WILLIAM H. FULLINGTON.
